United States Patent Office.

WILLIAM S. COLWELL, OF PITTSBURG, PENNSYLVANIA.

Letters Patent No. 74,809, dated February 11, 1868.

IMPROVEMENT IN MACHINES FOR DRESSING STAVES.

The Schedule referred to in these Letters Patent and making part of the same.

TO ALL WHOM IT MAY CONCERN:

Be it known that I, WILLIAM S. COLWELL, of Pittsburg, in the county of Allegheny, and the State of Pennsylvania, have invented a certain new and useful Improvement in Stave-Dressing Machines; and I do hereby declare the following to be a full and exact description thereof, reference being had to the accompanying drawings, and to the letters and figures of reference marked thereon.

The nature of my invention consists in providing a stave-dressing machine with a feeding-ram furnished with flexible centring-wings, and so arranged with relation to its driving-gear that it will unship itself from said gear and be drawn back by means of a weight or spring, said feeding-ram being combined with adjustable and yielding guide-rollers, and said ram and rollers combined with a stave-dressing head, the whole being constructed, arranged, and operating in the manner and for the purpose hereinafter described.

To enable others skilled in the art to make and use my invention, I will proceed to describe its construction and operation. In the accompanying drawings which form part of my specification—

Figure 1 is a top view of my improvement in stave-dressing machines.

Figure 2 represents a side elevation of the same.

Figure 3 represents a transverse section of the stave-dressing head and guide-rollers when cut through at line 20.

In the drawings, A represents the frame of the machine, which is placed on pedestals X. To the frame are secured bearings, B³, upon which are secured slides, B², to which are fitted guides, 1, which are attached to the sides of the feeding-ram A¹, the under side of which is provided with gear-teeth, which are adapted in form and size to the teeth of the wheel A³, secured on the shaft i, one end of which can be raised or lowered by means of a plumber-block, marked P, which is pivoted by means of ball-joint at the point marked X¹. On the under side, and near to the outside of the frame A, is secured a hanger, q, to which is pivoted a lever, C¹, to which is pivoted an arm, D¹, which is provided with a latch, t, and lug, X⁴, to which is attached a rod, f¹, which is secured to lug X⁴, and adjusted by means of screw-nuts 10. On the upper side of the frame A is pivoted a latch, Y, which passes through an opening, O in lever n, and to the outer end of this latch, Y, is attached a spring, S, which is secured to the side of the frame A. On the side of the feed-ram A¹ is an arm, u, which is provided with a slot, 8, and is held in the desired position by means of a set-screw, 9. The front end of the feed-ram A¹ is provided with two wings, 4, which are pivoted to the ram at the point marked 5. These wings are held in the desired position by the slides B², and when said wings are spread out, by coming in contact with the adjustable rollers 18, the back motion of the feed-ram A¹ will bring the wings in contact with the slides B², which will again bring the wings 4 into the desired position, and so arranged that the end of the timber from which the stave is formed will, when placed within their reach or grasp, be guided and brought central to the plane of the ram A¹, the point, 22, of which forms a semicircle, so that the pressure of the ram against the timber will always be on a line with the central plane of the ram. To the back end of the ram A¹ is attached a cord or chain, w¹, which passes over the pulley 16 in the upright piece 19, and to the end of the cord or chain w¹ is attached a weight, w. The head-block B is secured on the frame A, and extends a little beyond the end of the frame. To this head-block are secured the stave-dressing head and the guide-rollers. The frame B¹, in which the guide-rollers 18 are pivoted, can be moved in the guide R by means of a screw, 2, and thereby adjust the rollers so that the timber can be shaved off more on one side than on the other, or adjusted to shave equally on both sides. The rollers 18 also prevent the knives of the stave-dressing machine from "shriving," splitting, or biting into the timber beyond the contour of the stave. The rollers 18 are held in line by means of suitable bearings combined with spiral springs marked 1. The stave-dressing head is pivoted to the plate marked 24, the point of the pivot being on a line with the cutting-edge of the knives, marked J, which are provided with detached and convexed backs marked K, held in position by means of the parts C, 14, and 15, and adjusted by means of the set-screws marked 6. The knives are adjusted and held in the desired position by means of the set-screws 13 and keys 7. The bottom part, 15, of the stave-dressing head is provided with gear-teeth, marked X², (see fig. 3,) into which gear the teeth X³ on the lower end of the shaft, marked O, which is held in position by the part marked l. m represents a lever, used for operating the shaft O. On each side of the head-block

B are secured springs D, the points of which press against the sides of the part 15, and are so arranged that the space between the knives J will be kept in line with the plane of the ram A¹.

As the construction and arrangement of the several parts, and the relation they bear to each other, will be readily understood from the above description, and by reference to the accompanying drawings, I will therefore, without further description of the construction, proceed to describe the operation of my improved stave-machine.

The timber from which the stave is formed is placed with one end between the wings 4 of the feed-ram A¹, and the other end arranged so that it will enter between the guide-rollers 18. Power being applied to the pulley e, the pinion g will revolve the wheel h, shaft i, and pinion A³. I then press down on the lever C¹, which will raise up the arm D¹, which will raise up the plumber-block P, which will bring the pinion A³ into gear with the rack A² on the under side of the feed-ram A¹, and the motion of the pinion A³ will move the feed-ram A¹ forward until the arm u comes in contact with the lever n, and forces it back until the latch Y is drawn from under the latch t of arm D¹, which will allow the arm D¹ and plumber-block P to drop down, and thereby unship the pinion A³ from out of gear with rack A² of the feed-ram A¹, which will be drawn back by the weight w. When another piece of timber is placed in the machine in the manner before described, the front end of the piece being placed against the back end of the first piece, the forward motion of the second piece of timber will force the first piece from between the guide-rollers 18 and through and between the knives J. The circular or convex form of the back pieces K of the knives J will break back the shavings and prevent any biting into the stave beyond the cutting-edges of the knives J. The direction of the cutting of the knives is controlled by the operator through the medium of the lever m, and the timber may be cut away more on one side than on the other by simply moving the guide-rollers 18 sideways, through the medium of the screw 2. By pivoting the cutting or shaving-head at a point which is midway between the knives J, and on a line with the vertical plane of their cutting-edges, the tendency to side action of the knives is avoided, other than that given them by the operator through the medium of the lever m, for the purpose of causing the knives to follow the curves of the timber from which the stave is formed, for it is observed that any side action of the knives, other than that given by the operator, is a very great objection in stave-dressing machines. When the cutting-head is pivoted back of the cutting-edges of the knives they will be very liable to side action when any unsteady action of the stave-timber is brought against them.

Now, I wish it clearly understood that I do not claim broadly pivoting the cutting-head in a stave-dressing machine, for that is well known.

What I claim as my invention is—

1. The arrangement of the arm u, lever n, spring s, lever C¹, provided with arm D¹ and rod f¹, plumber-block P, wheel A³, feed-ram A¹, and weight w; constructed, arranged, combined, and operating as herein described, and for the purpose set forth.
2. The plumber-block P, provided with the universal or socket-joint X¹, said plumber-block being used in connection with shaft i, wheel A³, and the rack A² of the feed-ram A¹, as herein described and for the purpose set forth.
3. Providing the feed-ram A¹ with wings 4, which are opened or spread out by rollers 18, and contracted by the slides B², as herein described and set forth.
4. Pivoting the dressing-head of a stave-machine on a line with the vertical plane of the cutting-edges of the knives, the whole being constructed, arranged, and operating as herein described and for the purpose set forth.

W. S. COLWELL.
